[57] CLAIM

The ornamental design for a gun cabinet, substantially as shown and described.

DESCRIPTION

FIG. 1 is a perspective view of our gun cabinet in a closed condition, showing our new design;

FIG. 2 is another perspective view of our gun cabinet in an opened condition;

FIG. 3 is a front perspective view thereof but on a larger scale;

FIG. 4 is a front perspective view of a second embodiment of our gun cabinet, as shown in FIG. 1;

FIG. 5 is a sectional view taken along line 5—5 of FIG. 4 but on a reduced scale; and

FIG. 6 is another sectional view taken along line 6—6 of FIG. 4, but also on a reduced scale.

The rear and the one side of the gun cabinet not shown in the drawing are substantially plain and unornamented.
